CARVING FORK OR SIMILAR ARTICLE

Franz Wagner, Chicago, Ill., assignor to Ekco Products
Company, Chicago, Ill., a corporation of Illinois

Application April 2, 1956, Serial No. 40,862

Term of patent 14 years

(Cl. D44—29)

Fig. 1 is a front elevational view of a carving fork or similar article, showing my new design.

Fig. 2 is a side elevational view thereof.

Figs. 3, 4 and 5 are cross-sections taken on lines 3—3, 4—4 and 5—5, respectively, on Fig. 1.

Fig. 6 is an enlarged fragmentary section taken along line 6—6 of Fig. 1.

The essential features of the design reside in the portions shown in full lines.

I claim:

The ornamental design for a carving fork or similar article, as shown and described.
